UNITED STATES PATENT OFFICE.

HERBERT E. FISHER, OF SAN FRANCISCO, CALIFORNIA.

TYPE-PLATE.

1,285,094.

Specification of Letters Patent. Patented Nov. 19, 1918.

Application filed June 6, 1918. Serial No. 239,328.

To all whom it may concern:

Be it known that I, HERBERT E. FISHER, a citizen of the United States, residing in the city and county of San Francisco and State 5 of California, have invented a new and useful Improvement in Type-Plates, of which the following is a specification.

My invention relates to improvements in type wherein a flexible plate is used in conjunction with supports to suspend a type 10 slightly above the surface of a plane or drawing upon which it is to be impressed.

In lettering maps and other drawings a uniform style or type of lettering is required 15 not only by the United States Government but by many private concerns as well. When various drawings or maps are executed by different draftsmen the type of letter varies with the skill of the draftsman.

20 The object of the present invention is to provide a type of uniform design and size which may be readily placed or alined in proper position relatively to other letters in the same word and impressed upon a plane 25 surface such as a map or other drawing.

A further object of the invention is to provide improved means whereby all maps and drawings prepared by various draftsmen will have the same type and style of 30 lettering executed with equal skill.

A still further object of the invention is to provide improved means for lettering maps and drawings quickly and neatly effecting a saving of time.

35 It is also an object of the invention to provide a type of the character described having means for supporting the type slightly above the surface upon which it is to be impressed to prevent premature printing and 40 to also prevent soiling the map or drawing with the ink on the face of the type.

I accomplish these and other objects by means of the device disclosed in the drawings forming a part of the present specification 45 wherein like characters of reference are used to designate similar parts throughout the said specification and drawings, and in which:—

Figure 1 is a broken portion of a map 50 disclosing the manner in which the type is operated;

Fig. 2 is an enlarged side elevation of the type; and

55 Fig. 3 is a bottom plan view of the type. Referring to the drawings the numeral 1 is used to designate a transparent flexible

plate, preferably rectangular in shape, upon the under side of which is mounted a transparent raised type 2 of any suitable design. Supports 3 are placed on each corner of the flexible transparent plate 1 and at a distance from the type 2 thereon so that the said plate 1 may be deflected or bent sufficiently to bring face of the type 2 thereon into contact with a plane surface 6 upon 60 which the type 2 is to be impressed, the supports 3 being of slightly greater thickness than the thickness of the said type 2.

By means of the supports 3 the plate 1 is supported above the plane 6 a distance 70 which will in turn support the lower face of the type 2 a slight distance above said plane as disclosed in Fig. 2 of the drawings.

Two of the supports 3 and one edge of the plate 1 are beveled in the same plane and 75 toward the edge of said plate 1 as disclosed at 4 in Fig. 2 of the drawings.

In operation the proper letters are selected and inked by any suitable means, such as inking roller or pad not shown, and the 80 plate 1 is moved to its proper position as disclosed in Fig. 1 of the drawings, with the top and bottom of the type 2 alined with guide lines 8 on the map or drawing 7.

The alinement of the type 2 is facilitated 85 by the transparency of the plate 1 so that the proper and correct position of the type 2 may be obtained before said type is impressed upon the map 7 or other drawing.

The impression is made and the ink on 90 the face of the type is transferred to the map 7 or other drawing by placing a pressure with the thumb or other object on the direct center of the plate 1 and opposite the type 2 on the under side thereof.

When the pressure is released the elasticity of the plate 1 will immediately raise the face of the type 2 from the plane surface 6 or map 7 so that the type may be easily removed without smearing the ink or blotting 100 the impressed letter.

Another method of placing the type in alinement where the letters are to be placed in a straight line is to provide a ruler or other straight edge, not shown, against 105 which the beveled surface 4 resting flat upon the plane surface 6 is disclosed in dotted lines in Fig. 2 of the drawings. After so placing the plate 1 may be laid flat upon the plane surface 6 and impressed in the 110 manner hereinbefore described.

The beveled edge may also be used for re-

moving the plate 1 after the impression is had. By pressing downward upon said beveled edge the plate 1 will be raised from the drawing to the inclined position indicated 5 in dotted lines in Fig. 2 of the drawings and when in this position is easily and readily removable from the drawing.

The type 2 is also transparent so that the ink may be observed thereby indicating when 10 sufficient ink has been placed upon the type 2 to insure a good, black and sharp impression.

It is obvious from the foregoing that I have provided an improved type for letter- 15 ing maps and other drawings whereby the alinement of the letters may be facilitated. It is also evident that I have provided improved means for standardizing letters as 20 well as improved means for lettering maps and drawings.

I have also provided improved means for supporting the face of the type to be impressed above the surface upon which such impression is to be made whereby the type 25 or device may be moved into alinement without prematurely printing an impression.

The same means is adapted to immediately and automatically raise the type from the plane surface upon which it has been impressed as soon as said impression has been 30 accomplished.

Having thus described my invention what I claim as new and desire to secure by Letters Patent is—

35 1. A type comprising a flexible plate; a type mounted upon the under side of the plate; and means for supporting the face of the type slightly above a plane on which it is to be impressed.

40 2. A type comprising a flexible plate; a type mounted upon the under side of the flexible plate; and means secured to the un-

der side of the plate for supporting the same a slight distance above a plane on which the type is to be impressed said flexible plate 45 arranged to be impressed to impress the type onto said plane.

3. A type comprising a flexible transparent plate; a type mounted upon the under side of the plate; and means secured to the 50 plate for supporting the under face of the type a slight distance above a plane upon which said type is to be impressed.

4. A type comprising a flexible transparent plate; a type mounted upon the under 55 side of the plate; and means secured to the corner of the plate to support the face of the type thereon slightly above a plane upon which the type is to be impressed.

5. A type comprising a flexible transparent plate; a transparent type mounted upon the under side of the plate; and means secured to the corners of the flexible plate to support the type a slight distance above a plane upon which the type is to be impressed 60 whereby the approximate center of the plate may be impressed to impress the type onto said plane.

6. A type comprising a flexible transparent plate; a transparent type mounted upon the under side of the plate; a transparent support mounted upon each corner of the under side of the plate to support the type a slight distance above a plane upon which the type is to be impressed whereby the center 75 of said plate may be depressed to impress the type upon said plane, two of said supports being beveled in the same plane and toward one edge of the plate whereby the plate may be inclined for alinement before 80 being laid upon said plane surface.

In witness whereof I hereunto set my signature.

HERBERT E. FISHER.
